UNITED STATES PATENT OFFICE.

PAUL GERHARD STRASSMANN, OF CREFELD, GERMANY.

CLOSURE FOR VERTICAL RETORTS.

Application filed November 2, 1925, Serial No. 66,415; and in Germany May 31, 1924.

This invention relates to a sealing means for vertical retorts, generating chambers or the like, and more particularly to a combined "wet" and "dry" sealing means for producing a reliable connection between the retort proper and the detachable floor or bottom portion thereof.

The means of the "wet" or liquid type hitherto proposed for sealing the bottoms of vertical retorts, generating chambers or the like (hereinafter termed merely the "retort") suffer under the disadvantage that the material in the retort to be gasified, or also the filling material which is employed to fill up the lower, unheated part of the retort, falls down into the water, i. e., the channel or trough, and becomes saturated. The capillary action of the finely granulated material sucks up the water, which enters into contact with the refractory material of the lower walls of the retort. This results in the refractory material being attacked thereby, and this may even be carried to such extent that the strength of the retort is greatly undermined.

More earlier proposals provide for a short annular extension to the lower part of the retort, which is made to dip into a small dry channel and prevents the filling material from dropping into the actual water channel or trough, which is situated outside of the dry channel. This arrangement, however, has the disadvantage that the detachable floor or bottom portion together with the channel possesses considerable width, and cannot be easily brought into position underneath the retort.

It has therefore also been proposed to construct the detachable floor with a raised or elevated portion projecting into the interior of the retort in such manner that the material to be gasified is neither able to fall into the water channel nor into the unheated part of the retort. In this case the "dry" sealing means is situated at such height within the retort that the unheated part of the retort is kept free from the material to be gasified. In the case of this arrangement difficulty in construction of no mean kind is met with in the embodiment of the lower, unheated part of the retort, as the raised or elevated part to the floor or bottom portion in view of the rotary movement about a laterally disposed axis does not allow the walls of the retort to be extended

vertically to the lower plane of the floor.

With large retorts, however, a firm support for the heavy walls is an essential condition for the strength.

The object of the present invention is to overcome these said drawbacks without losing any of the advantages of the constructions referred to.

The invention is shown by way of example in the accompanying drawing, which illustrates the bottom of the retort with the improved sealing means in vertical section.

Referring to the drawing, the lower or "wet" sealing means consists of a water channel or trough *a*, the floor or bottom of the retort being pivotable about a laterally disposed hinge bolt *b*. Beneath the aperture of the retort the floor or bottom part is furnished with a raised or elevated portion *c*, which extends up beyond the level of the water in the channel *a*. The lower part of the retort is supported by means of a flanged metal ring *d*, which dips into the water channel *a*, and thus produces a "wet" gas-tight method of sealing.

The lower closure ring *d* of the retort also possesses on the inner edge a packing shoulder or ledge *e*, against which rests the circumferentially projecting edge of the elevated portion *c*. The closure between the packing shoulder *e* and the elevated portion *c* need not be gastight, but merely sufficiently dense to prevent the filling material, which fills out the unheated part of the retort and supports the material to be gasified, from being able to drop into the water channel *a*.

The advantage of this arrangement consists in the compact construction of the whole sealing means as regards the width, so that the same may also be applied to retorts which are situated closely together; also in the fact that the elevated portion *c* need not be higher than the remaining part of the floor or bottom part including the water channel, so that when the floor or bottom portion hangs downwards the same does not come within the space underneath the retort representing the interior diameter thereof, which is otherwise the case in connection with densely spaced retorts.

The great disadvantage of the ordinary "wet" sealing means without a second means of the "dry" variety, viz, the sucking up of the sealing water and the consequent de-

struction of the refractory material in the retort, is completely avoided without losing the advantages otherwise attained, viz., a slow vaporization of the sealing water by the radiating heat of the lower part of the retort, which would otherwise be entirely lost in the form of heat radiation from the floor or bottom portion. The steam formed in the channel *a* is able, as before, to reach the interior of the retort in view of the fact that the closure formed by the elevated portion *c* and the packing shoulder or ledge *e* is not gastight.

What I claim is:

In combination, a retort having a lower closure ring, said ring having an annular packing shoulder thereon, a hinged door member having an annular trough portion adapted to receive the closure ring and a sealing liquid, said door having a central elevated portion engaging the packing shoulder of the closure ring.

In testimony whereof I have affixed my signature.

PAUL GERHARD STRASSMANN.
